UNITED STATES PATENT OFFICE

2,268,950

STATION INDICATING MEANS FOR
AUTOMATIC TUNERS

Le Roy J. Leishman, Los Angeles, Calif.

Application December 1, 1937, Serial No. 177,434

9 Claims. (Cl. 116—124.1)

This invention pertains to automatic tuning devices for radio sets and the like, and more particularly to those having a series of manually movable arms each of which is adapted to tune in a pre-selected station after an initial adjustment has been made. In devices of this kind that are operated by levers, it is customary for the levers to be provided with springs that return them after each operation to a rest, or inoperative, position. As a consequence, it is impossible to tell what station the set is tuned to by looking at the controls, and the tuning scale must therefore be referred to. Even this method of identification is not satisfactory unless one is able to identify the stations by their dial readings. The present invention is directed toward the elimination of this difficulty. Its objects are to make it possible instantly to identify the station to which the set is tuned; to provide means for illuminating the index tab for such station; to afford a mechanism whereby the subsequent tuning in of a different station will automatically extinguish the illumination of the tab for the station previously tuned in; and to provide means whereby only one adjusting screw at a time is made accessible. Still other objects will appear as this description proceeds.

In the accompanying drawing:

Fig. 1 is a side elevation of an automatic tuning mechanism equipped with applicant's invention for selectively illuminating the station index tabs.

Fig. 2 is a front elevation of part of the mechanism shown in Fig. 1, taken on line 2—2 of Fig. 1.

Fig. 3 is a plan view of the guides for the movable shutters, and is a section taken substantially on line 3—3 of Fig. 2.

Fig. 4 illustrates a modified shutter arrangement in which the shutters move only a fraction of the distance required for the shutters shown in the previous figures, but which does not completely admit or exclude the light.

Fig. 5 is a cross section of Fig. 4 taken on line 5—5.

In Fig. 1, A1, A2 and A3 are rotatable levers, each having a curved arm and a relatively straight arm bearing a set-screw R. The operating levers F1 and F2 move in the same planes respectively as rotatable levers A1 and A2. The operating levers are all pivoted on a common shaft Q, and the rotatable levers are mounted in various angular positions on shaft S, which is used to transmit rotatory motion to the condenser gang. If the operator's finger is placed on button W1 and lever F1 pressed as far down

as it will go, it will assume the position shown in dotted lines and indicated by the reference characters F1a. This will move positionable lever A1 to the position shown, regardless of the position in which it might be when engaged by lever F1 in its downward movement. Should lever A1 happen to be in the angular position of lever A3, it will be obvious that the operating lever would engage the end of the straight arm, causing it to rotate with the downward motion of the operating lever. If the straight arm of the positionable lever is found below shaft S in an angular position 180 degrees from that of lever A3, the rounded arm K3 would be above shaft S, and the downward movement of the operating lever would then engage this rounded end and rotate the positionable lever to the angular position in which A1 is pictured. From the foregoing description, it will be evident that any positionable member may be rotated to the position in which member A1 is shown merely by pressing down the associated operating lever. Shaft S may therefore be turned to any desired angular position by any of the operating levers, providing the cooperating positionable lever has been pre-set in that position on the shaft while the operating lever is held down.

The pre-setting operations are performed in the following manner: Cover strip I is removed from escutcheon D by taking out screws P—one on each end of the strip. One of the operating levers, say F1, is then pressed down. This brings set-screw R behind hole X1 in bar Y and into alignment with hole U in the escutcheon. With the lever still held down, a screw-driver is inserted through these holes and the set-screw loosened. Shaft S may then be turned while the positionable lever is held stationary. Inasmuch as shaft S is operatively connected to the tuning condensers of the radio set, the manual tuning in of a desired station will turn shaft S to an angular position with relation to the positionable lever that will always be the same for that station. After the station has been carefully tuned in, the set-screw is again tightened, and the cover strip is replaced. Any subsequent pressing of lever F1 will automatically tune in this station. Other operating levers will bring in other stations if the cooperating positionable members are set in the manner just described.

Levers F1 and F2 are provided with springs J1 and J2 for returning them to their rest position against bumper B, which in the form disclosed is a tube of rubber around rod Q1. Other levers, not shown, are equipped with such springs, and

since all the levers therefore flip back up after each operation, it is impossible to tell what station is tuned in unless the dial is consulted. No dial is shown in the drawing, as the dial forms no part of this invention. To obviate the inconvenience of referring to the dial readings to identify the station that is tuned in, the present invention provides means for illuminating the index tab for the lever last operated.

In Fig. 1, the station label or index tab O is shown in a recess between the holder M and the escutcheon D. Holder M has a window N through which the tab may be seen from the front of the set, and the escutcheon has a window Na through which the tab is illuminated. Member G, Fig. 2, extends across the front of the tuner assembly from one end plate to the other, and is provided with windows T1, T2, T3—one for each index tab. Member G has a perpendicular projection 6 at the top and another projection 7 at the bottom. Projection 7 is stamped, as shown in Fig. 3, to form guides for vertical members C1, C2, C3 and C4, Fig. 2, with their shutter projections V1, V2, V3 and V4.

Members C1 to C4 are movably fastened at the bottom by ears Z1, Z2, Z3 and Z4, which may be punched on bar Y, and which fit into slots 8 of members C1, C2, C3 and C4 respectively. These vertical members each have a slot 9 near their upper ends. Down the center of each of these slots extends a tongue 10, which is integral with the member. An expansion spring 11 surrounds each tongue 10. One end of each spring 11 presses against guide member 7, and the other end forces the vertical member upward against bumper B2.

Member G has a series of lugs 14 for preventing lateral movement of the upper ends of the vertically movable members.

When the sliding shutter members are in their normal position against bumper B2, light from the lamp L is intercepted by the shutter projections V1, V2, V3 and V4, thus preventing the illumination of the index tabs, as no light can then pass through the corresponding windows T1, T2, T3 and T4, but if one of the levers, say F1, is depressed, the lever engages projection 12 on member C1 and pulls the shutter member down to the position shown in Figs. 1 and 2, with the shutter V1 below window T1, permitting the light to pass through windows T1 and Na, Fig. 1, and illuminate tab O. The operating lever then occupies the position indicated by F1a in Fig. 2. The shutter is held in this lower position by latch bar E, which engages projection 15a formed on the shutter, but the operating lever returns to its original position. The latch bar extends all the way across the tuning device and lies in the path of projections 15a, 15b and 15c on all the shutters. On one end of the latch bar a spring J3 is fastened above the pivot Q3, which may be integral with the bar, or a rod or stud journaled in end plate 17a. The other end of this spring is fastened to stud Q4. The tension of this spring pulls the latch bar against pin Q5 on plate 17a. At its other end, the bar has a pivot Q6, Fig. 2, in end plate 17b, and a spring J4 acting in conjunction with spring J3 previously described. The subsequent tuning in of a different station by another lever, say F2, engages tappet 12 on member C2, and as the lever and member move down, the tapered edge of hook 15b, Fig. 1, presses against the latch bar, releasing 15a. This, of course, causes member C1 to flip up and shutter V1 masks window T1.

shutting off the light to tab O, Fig. 1. As projection 15b moves downward, it in turn is locked in position as soon as it passes the lower edge of the latch bar. Shutter V2 is then below window T2, and the associated index tab, not shown, then become the illuminated one. The operating lever then returns to its rest position against bumper B.

From the foregoing description it will be clear that the illuminated index tab always indicates the lever that was last pressed down.

The same result may be attained without the shutters by providing each index tab with an individual lamp and using similar latch-controlled members to operate switches that are individual to the lamps. I prefer, however, the embodiment of the invention shown in the figures, as it permits the illumination of the tabs by the same lamps used for the dial, is less expensive, and does not entail difficulties due to faulty contacts or the burning out of the lamps.

If the index tabs are placed above the levers as shown in the drawing, instead of below the levers as in my Patent No. 2,084,851, the removal of strip I, Fig. 1, reveals all the set-screw holes X1, X2, X3 and X4 in bar Y. Only one set-screw, however, will be in perfect alignment with the corresponding hole, and that one will be the set-screw for the positionable member cooperating with the operating lever that was last pressed down; but the set-screws for any positionable levers that have been set at only slightly different angular positions will also be visible through the adjusting holes. This sometimes causes confusion to a novice which is adjusting the device to bring in a group of desired stations, or who may be changing the station for a given lever. To overcome this difficulty, the present invention provides means for covering all the set-screws except the one in the lever that is to be set. The vertically movable members C1, C2, C3 and C4 are provided with masking portions 16a, 16b, 16c and 16d, that cover the adjusting holes when members C are in their upper positions. When one of these members is pressed down, however, the opening 13 reveals the corresponding set-screw hole, as shown by opening 13 in vertically movable member C1, Figs. 1 and 2.

It may be thought desirable to have all the index tabs dimly illuminated at all times and the index tab for the tuned-in station merely illuminated to a greater degree, or to achieve the objectives of this invention with a vertically movable member having less travel than the arrangement previously described. This may be accomplished by the modification shown in Figs. 4 and 5. In this arrangement, each of the windows T1, T2 and T3 of the preceding figures is replaced by a series of openings Ta, and shutter V has a series of openings or transparent sections Tb that are normally hidden behind the solid portions between the openings Ta. If shutter V is moved down a distance equal to the height of one of these openings, an examination of Figs. 4 and 5 will disclose the fact that openings Tb will register with the lower two openings Ta, thus permitting light to pass therethrough, and that light may also pass through the higher of the Ta openings because the upper opaque section of the shutter will have moved behind the solid section between the two higher openings in member G. This embodiment of the invention of course requires much less longitudinal movement of members C than the arrangement previously described in which the

shutters either lie behind or completely below windows T.

It will be understood that my selective index-tab illuminating means may be used with any tuner having a manually movable member for each of a group of pre-selected stations, and that the form of tuning mechanism shown in Fig. 1 is described in this specification merely to illustrate the use of the present invention with tuners of this general type.

While I prefer the form of my invention shown in Figs. 1, 2 and 3, it will be obvious that various modifications may be made from the embodiments disclosed without departing from the spirit of the invention.

My claims are:

1. In a radio tuning apparatus having a movable control element and a plurality of means for effecting the movement of said element each to a predetermined position and each comprising an independently operable manual, indicating means including, in combination, a light source; an index tab for each of said manuals; a movable shutter for each index tab adapted to screen said tab from light from said source when said shutter is in a restive position; and a plurality of means each individual to one of said manuals for moving the associated shutter from said restive position upon operation of the associated manual.

2. In a radio tuning apparatus having a movable control element and a plurality of means for moving said element each to a predetermined position and each comprising an operating device, a combination for indicating the last device operated, said combination including, a light source; an index tab for each of said operating devices; a movable shutter for each index tab adapted to screen said tab from light from said source when said shutter is in a restive first position; said shutter movable to a second position that will permit light from said source to illuminate said tab; means for locking said shutter in said second position; and a plurality of means each individual to one of said operating devices and to one of said shutters for moving the associated shutter from said first position to said second position upon operation of the associated operating device.

3. In a radio tuning apparatus having a movable control element and a plurality of means for effecting the movement of said element each to a predetermined position and each comprising an operating member movable independently of the other operating members, an indicating means including, in combination, a light source; an index tab for each of said operating members; a movable shutter for each index tab adapted to screen said tab from light from said source when said shutter is in a restive first position; said shutter movable to a second position in which it does not screen said tab from said light; means for locking said shutter in said second position; and a plurality of means each individual to one of said operating members and to one of said shutters for moving the associated shutter from said first position to said second position upon operation of the associated operating members; and means for unlocking said shutter upon the subsequent operation of any other of said operable means.

4. In a radio tuning apparatus having a movable control element and a plurality of independently operable means for effecting the movement of said element each to a predetermined

position, an indicating means comprising, in combination, a light source; an opaque shield having a plurality of windows therein; and a movable shutter for each window adapted to screen said window from light from said source when said shutter is in a first position; said shutter movable to a second position in which it does not screen said window from said light; and a plurality of means each individual to one of said operable means and to one of said shutters for moving the associated shutter from said first position to said second position upon operation of the associated operable means.

5. In a radio tuning apparatus having a positionable tuning element and a plurality of independently operable means for effecting the movement of said element each to a predetermined position, an indicating means comprising, in combination, a light source; an opaque shield having a plurality of windows therein; a movable shutter for each window acting to screen said window from light from said source when said shutter is in a first position; said shutter movable to a second position in which it does not screen said window from said light; a plurality of means each individual to one of said operable means and to one of said shutters for moving the associated shutter from said first position to said second position upon operation of the associated operable means; means for locking said shutter in said second position; and means for unlocking said shutter upon the subsequent operation of any other of said operable means.

6. In a radio tuning apparatus having a positionable tuning element and a plurality of independently operable positioning means for effecting movement of said element each to a predetermined position, an indicating means comprising, in combination, a plurality of index tabs; means for illuminating said tabs comprising a light source; a plurality of movable members each individual to one of said tabs and held by a retaining spring in a first position in which said member intercepts light rays passing from said source to the tab associated with said member; each of said members having means by which it is moved by one of said positioning means to a second position in which said member does not intercept said light rays; means for locking said member in said second position; and means for unlocking said member upon the subsequent operation of any other of said positioning means.

55 7. In a radio tuning apparatus having a positionable tuning element and a plurality of independently operable positioning means for effecting the movement of said element each to a predetermined position, an indicating means comprising, in combination, a plurality of index tabs each individual to one of said positioning means; means for illuminating said tabs comprising a light source; a plurality of movable members each individual to one of said tabs and to one of said positioning means, each of said members normally held by a retaining spring in a first position in which said member intercepts light rays passing from said source to the tab associated with said member; each of said members adapted to be engaged by the associated positioning means and moved to a second position in which said member does not intercept said light rays; and a latching means adapted to lock any of said members in said second position; each of said members having means to

actuate said latching means to unlock the previously locked member.

8. In a radio tuning apparatus having a positionable tuning element and a plurality of selectively operable positioning means for effecting the movement of said element each to a predetermined position and each comprising adjustable position-predetermining means having a screw for maintaining the adjustment thereof, a combination including: a shield having apertures individual to each of said screws; an index tab for each of said positioning means; means for illuminating said tabs comprising a light source; a plurality of movable members each adapted to mask one of said apertures and to substantially shield one of said tabs from light from said source; and a plurality of means each individual to one of said members and operable by one of said positioning means for moving the associated member to a position in which it does not mask the associated aperture and shield the associated tab.

9. In a radio tuning apparatus having a posi-

tionable tuning element and a plurality of selectively operable positioning means for effecting the movement of said element each to a predetermined position and each comprising an adjustable device held in adjustment by a screw for predetermining said position, a combination including: a shield having apertures individual to each of said screws; an index tab for each of said positioning means; means for illuminating said tabs comprising a light source; a plurality of movable members each adapted to mask one of said apertures and to substantially shield one of said tabs from light from said source, each said member engageable by one of said positioning means and movable upon operation of said positioning means to a position in which it does not mask said aperture nor shield said tab; means for locking said member in said position; and means for unlocking said member upon the subsequent operation of another one of said positioning means.

LE ROY J. LEISHMAN.
